UNITED STATES PATENT OFFICE.

FREDERICK WILLIAM MEAD, OF SOLIHULL, ENGLAND.

LUBRICATION SYSTEM OF INTERNAL-COMBUSTION ENGINES.

Application filed May 13, 1922. Serial No. 560,630.

To all whom it may concern:

Be it known that I, FREDERICK WILLIAM MEAD, a subject of the King of England, residing at Solihull, in the county of Warwick, England, have invented certain new and useful Improvements in Lubrication Systems of Internal-Combustion Engines, of which the following is a specification.

This invention relates to internal combustion engines of the type in which the valves are actuated by a camshaft arranged above the cylinder heads, and the object is to provide a simple means for lubricating the camshaft bearings and associated parts.

15 In the accompanying drawings,

Figure 1 is a side elevation partly in section of a four cylinder engine embodying this invention, and

20 Figure 2 is an end view of the same partly in section on the line 2—2.

Like letters indicate like parts throughout the drawings.

In this construction, a conduit A is arranged near the flywheel B, and the flywheel 25 dips into a sump C so that it forces oil up the conduit in the well known manner, enabling a separate pump to be dispensed with.

This conduit leads to a reservoir D in which is located the bearings E for one 30 end of the camshaft F. The reservoir may be of comparatively large capacity, and there may be a ring lubricator or some equivalent device to ensure the oil in the reservoir feeding the bearing for a long period even if the circulation of oil ceases.

From this reservoir extends a pipe G to another reservoir H arranged around the other camshaft bearing or bearings J. The pipe G is preferably arranged over the camshaft and has in it outlets such as K opposite each cam so that the oil is sprayed on to each cam, rocker, etc. Preferably the outlets are of comparatively large diameter and are obstructed to a varying extent by 45 means of an adjustable plug in each outlet, which may take the form of a split pin as shown. Thus if an outlet chokes up it is only necessary to move the split pin when it will automatically clean itself. Further, by varying the "spread" of the split pin the

amount of obstruction of the outlet may be varied and by this means it is possible to provide, in a very cheap manner, a very delicate feed of oil to each cam with easy means for cleaning.

The reservoir J is similar to the one D, and it has an overflow at J² into an adjoining compartment L in which is arranged the bevel or skew gearing M N driving the camshaft. From this compartment there is 55 an overflow O at a suitable height, which ensures there being always sufficient oil in the compartment L to lubricate the gears M N amply. The overflow leads through pipe 2 the crankcase P communicating with 60 the sump C.

By this means a very simple and cheap system is provided with means for ensuring certain lubrication should the circulation fail for a short period.

What I claim as my invention and desire to secure by Letters Patent of the United States is:—

1. In an internal combustion engine, the combination of valves in the cylinder head, 75 a camshaft, a bearing for one end of said camshaft, a chamber enclosing said bearing, means for supplying oil to said chamber, a second bearing at the other end of said cam- 80 shaft, a second chamber enclosing said second bearing, an overflow pipe from said first chamber adapted to conduct oil to said second chamber, outlets in said pipe adapted to feed oil on to said cams, a split obstruction in each of said outlets, gearing for 85 driving said camshaft, a chamber enclosing said gearing, an overflow pipe from said second chamber to second chamber enclosing said gearing, substantially as set forth.

2. The device of claim 1, said split ob- 90 struction including a split pin penetrating said over-flow pipe.

In testimony whereof I have signed my name to this specification in the presence of two subscribing witnesses.

FREDERICK WILLIAM MEAD.

Witnesses:

HARRY MOULD,
THOMAS WILLIAM DEAKIN.
